UNITED STATES PATENT OFFICE.

HIRAM PERCY MAXIM, OF HARTFORD, CONNECTICUT.

DESIGN FOR A VEHICLE-BODY.

No. 39,041.

Specification for Design.

Patented Jan. 28, 1908.

Application filed November 6, 1907. Serial No. 401,030. Term of patent 14 years.

To all whom it may concern:

Be it known that I, HIRAM P. MAXIM, a citizen of the United States, residing at Hartford, in the county of Hartford and State of Connecticut, have invented a new, original, and ornamental Design for a Vehicle-Body, of which the following is a specification, reference being had to the accompanying drawing, forming part hereof.

Figure 1 is a view in side elevation of a ve-

hicle body embodying my invention. Fig. 2 is a perspective view of the same.

I claim:

The ornamental design for a vehicle body, as shown.

HIRAM PERCY MAXIM.
